UNITED STATES PATENT OFFICE

CHARLES W. LEGUILLOON, OF AKRON, OHIO, ASSIGNOR TO THE B. F. GOODRICH COMPANY, OF NEW YORK, N. Y., A CORPORATION OF NEW YORK

METHOD AND APPARATUS FOR MANIPULATING TUBULAR TEXTILE MATERIAL

Application filed September 27, 1927. Serial No. 222,255.

This invention relates to procedure and apparatus for manipulating tubular textile material such as the stockinet commonly employed as the lining material for rubber foot-wear, the material usually being woven or knitted in tubular form as a matter of convenience in its manufacture and requiring to be slit longitudinally and rubberized in spread condition in preparation for use. 5 These operations heretofore have been attended by a good deal of difficulty because of the extreme stretchability and elasticity of the stock and its tendency to curl.

The chief objects of my invention are to provide improved procedure and apparatus for economically and accurately slitting the tubular stock, and especially for slitting it along a single line of cut. Further objects are to provide conveniently and economically 15 for rubberizing the slit stock, to avoid difficulty in holding the slit stock in spread condition, and to eliminate intermediate steps, such as reeling and transporting the stock, between the slitting and the rubberizing operations.

Of the accompanying drawings:

Fig. 1 is a side elevation of apparatus embodying and adapted to carry out my invention in its preferred form, a calender associated therewith being shown in section.

Fig. 2 is a section on line 2—2 of Fig. 1.

Fig. 3 is a plan view of the apparatus and the work therein, a part of the work being 35 broken away.

Fig. 4 is a section on line 4—4 of Fig. 3.

Referring to the drawings, the fabric slitting and spreading apparatus is here shown in combination with a calender 10, comprising a top, platen roll 11, a middle, coating or friction roll 12 and a bottom roll 13. Although the fabric is preferably rubberized by means of a calender or other device adapted to receive the fabric directly from the slitting and spreading means, other rubberizing de-

vices or simple reeling means may be substituted for the calender.

The slitting and spreading device comprises a guide or form 14 having a freely projecting, receiving-end section 15 which has a form such as results from flattening one end portion of a hollow cylinder while the other end remains circular, the flattened receiving end being of such size as to fit snugly within the stockinet tube 16 with the latter in flattened condition, and the circular end of the section 15 being of such size as to fit snugly within the stockinet tube in circular condition. Next to the section 15 the guide comprises a cylindrical section 17 constituting a part of its freely projecting portion and beyond that the guide comprises a section 18 which is of a form such as to provide for a feeding of the slit stock over its surface from a cylindrical tubular condition at the slitting position to a flatly spread condition without substantial deforming, or causing localized stretching of the stock in its progression to the spread condition, which is to say that all lines representing paths of travel of portions of the stock from the cylindrical portion 17 of the guide to the terminal flat portion of the guide are of substantially equal length.

The guide 14 is supported upon standards 19, 20 connected to the terminal portion 18 of the guide, the slitting of the stock by a driven rotary slitting knife 21 mounted adjacent the cylindrical portion 17 of the guide permitting the stock to pass the supporting standards 19, 20. The terminus of the guide 14 is in position to deliver the slit and flattened stock to the calender 10 and the calender is adapted to draw the stock over the guide 14 from a stock roll 16^a mounted upon standards 22, 22 adjacent the receiving end of the guide. A guide roll 23 is mounted in position to guide the fabric onto the guide 14 from the same direction notwithstanding variations in the size of the stock roll 16^a.

In order to prevent the slit stock from slid-

ing laterally out of proper alignment upon the terminal portion 18 of the guide, an endless belt 24 provided on its outer face with a longitudinal row of pins 25, 25 is mounted 5 upon pulleys such as the pulley 26 (Fig. 1) journaled under the respective end portions of the section 18, the belt 24 passing through slots in the section 18 and sliding upon the outer face of the said section between lateral 10 guides 18^a, 18^a thereon and driven by the fabric as the latter is drawn by the calender. The pins 25, successively penetrating the fabric at the slitting position and moving forward therewith to the delivery end of the 15 guide prevent lateral creeping of the fabric upon the guide section 18 in this movement and are withdrawn from the fabric at the delivery end of the guide by the passage of the belt downward through the latter.

20 To insure penetration of the fabric by the pins 25, a grooved roller 27 is mounted just over the pulley 26 at the receiving end of the belt's orbit, in position to engage the outer face of the fabric and prevent it from being 25 lifted by the pins, the pins extending into the groove of the roller 27, as will be clear upon reference to Fig. 2.

To brush the stockinet for the reception 30 of a sheet of rubber 28 in the calender, a stiff 30 rotary brush 29 may be mounted between the guide 14 and the calender, as shown in Fig. 1.

To assure a flatly spread condition of the side margins of the flattened fabric as it passes 35 into the nip of the calender, an air nozzle 30 is mounted at each side of the calender in position to direct the jet of air against the under face of the fabric and toward its side edge, the jets of air counteracting the tendency of the side margins of the fabric to curl down- 40 ward after they pass from the section 18 of the guide.

In the operation of the apparatus, the work 45 being started through the calender as shown, the calender continuously draws the tube of stockinet from the stock roll 16^a and over the guide, the rotary cutter 21 slits the stock along its other side as the stock passes from the cylindrical section 17 of the guide, the endless belt 24 with its pins 25 maintain the 50 stock in proper alignment as it passes over the guide section 18 to a flattened condition adjacent the calender rolls, the air nozzles 30 keep the side margins of the fabric flattened out against the top roll of the calender 55 and the stock is provided with a coating of rubber as it passes through the calender, from which it is received by any suitable means such as a stock reel (not shown).

The rubberizing of the stockinet fabric 60 immediately after it passes in flattened condition from the guide section 18 reduces the tendency of the fabric to curl at the edges and the rubberized fabric may be conveniently reeled or otherwise disposed of with- 65 out very great precaution against curling.

The flared and flattened receiving end portion of the guide section 15 causes the flattened tubular stockinet fabric to pass onto the guide without twisting such as to spoil the alignment and the cylindrical section 17 70 of the guide maintains the tubular structure in accurate unslackened or slightly tensioned condition for the slitting operation, and the apparatus as a whole provides for conveniently slitting the stock along a single line of 75 cut and progressively spreading the entire strip of fabric to flat form without at any time excessively stretching or slackening any part of the fabric.

Modifications are possible within the scope 80 of my invention as defined in the appended claims.

I claim:

1. Apparatus for manipulating tubular textile material, the said apparatus comprising a guide formed with a projecting end portion adapted to receive the stock thereon in tubular form, means for drawing the stock past said guide, and means for slitting the stock along a single line of cut longitudinally of the tube as it passes over the projecting portion of the guide, the guide being formed with a terminal portion so shaped that longitudinally the guide varies from an approximately cylindrical form to a substantially flat form, the effective width of the substantially flat portion being approximately equal to the circumference of the approximately cylindrical portion, and the surface between the two said portions being so shaped that all lines representing paths of travel of portions of the stock are of substantially equal length, for the sliding of the stock thereover from closed tubular form to a transversely flattened form without substantial localized stretching or slackening of the stock.

2. Apparatus for manipulating tubular textile material, the said apparatus comprising a guide formed with a projecting end portion adapted to receive the stock thereon in tubular form, means for drawing the stock past said guide, means for slitting the stock longitudinally of the tube as it passes over the projecting portion of the guide, the guide being formed with a terminal portion shaped for the sliding of the stock thereover from a tubular to a transversely flattened form without substantial localized stretching or slackening of the stock, and stock-engaging means mounted for actuation by the stock engaged therewith, to travel with the stock along the surface of the terminal portion of the guide to preserve alignment of the stock thereon.

3. Apparatus as defined in claim 2 in which the stock-engaging means defined comprises an endless, orbital member mounted for actuation by the stock engaged therewith and stock-penetrating projections thereon.

4. The method of manipulating tubular

textile material which comprises feeding the material in tubular form, progressively slitting it along a single line of cut longitudinally of the tube as it is so fed, and progressively flattening the material throughout its entire width as it passes from the slitting position, while maintaining the material substantially free from local stretching or slackening as it passes from tubular to flattened form.

In witness whereof I have hereunto set my hand this 24th day of September, 1927.

CHARLES W. LEGUILLOON.
